UNITED STATES PATENT OFFICE.

HOWARD M. LEONARD, OF SOUTH BEND, INDIANA, ASSIGNOR TO GERNANDT MOTOR CORPORATION, OF CHICAGO, ILLINOIS, A CORPORATION OF ILLINOIS.

FUEL-INJECTING MEANS.

Application filed June 21, 1926. Serial No. 117,648.

This invention relates to pumps and the like adapted, as one important use, to inject fuel charges into the engine cylinders of Diesel type engines. An object of the invention is to provide a pump plunger having a very close fit in its cylinder, and preferably formed with a novel fuel-feeding passage arranged to mix the charges as they are injected.

10 In one desirable embodiment, the pump plunger is axially divided to form parts which are yieldingly urged away from each other, for example by springs confined between them, into very close engagement with their cylinder. The parts may be connected, by a novel tongue-and-groove joint or the like, with an operating plunger aligned with the pump plunger.

As this gives all the clearance in the space 20 between the parts of the plunger, I prefer to utilize this space as part of a passage for feeding the compressed fuel mixture to the engine, by forming an opening from the outside of one part of the plunger to this 25 space between the parts, which opening at the end of the compression stroke of the pump is arranged to communicate with the engine cylinder.

As I consider it desirable that the plunger 30 parts be made so accurately that the clearance between them is quite small, I prefer to form one part of the plunger on its plane face with an axial groove extending from the end of the plunger and communicating with the above-described opening. If desired, at 35 least a part of the passage formed by the groove and opening may be of zig-zag form,—that is, it may be formed with a series of sharp bends,—to form baffles which 40 aid in breaking up and vaporizing the fuel charges.

In one modification shown in the drawing, there is a separate part in an undercut 45 groove in the plunger over the end of the radial opening, having a depression or cup over the end of that opening in which most of the compressed fuel charges collect, and having openings from the depression which communicate at the proper time with the engine cylinder.

50 The above and other objects and features of the invention, including various novel combinations of parts and desirable particular constructions, will be apparent from the following description of the illustrative em-

bodiment shown in the accompanying drawing, in which:

Figure 1 is a vertical section axially through the engine and pump cylinders;

Figure 2 is an end elevation of one form 60 of pump plunger;

Figure 3 is a development of the upper portion of one part of the plunger;

Figure 4 is a side elevation of a modified plunger;

Figure 5 is a side elevation, 90° from Figure 4, of the plunger;

Figure 6 is a cross section through the plunger on the line 6—6 of Figure 1 (or 4);

Figure 7 is a cross section through the plunger on the line 7—7 of Figure 4.

The invention is shown embodied in a fuel-injecting pump for a Diesel type engine including the usual piston 10 in the power 75 cylinder 12 having, if desired, a compression-relief valve 14 and formed with a combustion chamber 16 in the detachable head 18. The engine may have a water jacket 20. The particular engine illustrated is of the 80 two-cycle crankcase-compression type, although the invention is not limited to use with such engines.

The present invention relates to the pump for injecting the fuel. In both arrangements the pump includes a divided or multi-part plunger arranged in a pump cylinder 22, the plunger also acting as a valve injecting compressed charges of fuel and gases into the engine cylinder through one or more 90 passages 24, just before the engine piston 10 completes its compression stroke. As is usual in this type of engine, the air compressed by engine piston 10 is at this time at a sufficiently high temperature to ignite the 95 fuel. In the particular engine illustrated, the fuel charges are vaporized in carrying 100 charges of exhaust gases from the engine cylinder, although if preferred air, steam, or other carrying fluid may be used to form a rich vapor with the fuel.

The pump plunger includes two parts 26 and 28, divided diametrically with respect to the pump cylinder, and with openings 24 approximately opposite the center of part 26. Parts 26 and 28 are provided at their lower ends with tongues 30 and 32 interlocking as a tongue-and-groove joint with an undercut groove formed by flanges 34 extending, parallel to the plane dividing 110

parts 26 and 28, across the top of an operating plunger 36. Parts 26 and 28 are urged away from each other by a plurality of springs confined between them, here illustrated as two coil springs 38 in sockets formed on the inner sides of the plunger parts (see Figure 6).

The plunger of Figures 1-3 has an axial groove 40 along the plane face of part 26, 10 preferably of zig-zag form (i. e. formed with a series of sharp bends), which is connected by an opening 42 and a radial zig-zag groove 44 with a short straight groove 46 which registers with passage 24 when the pump 15 plunger is at the uppermost end of its stroke.

The fuel passage of the plunger of Figures 4, 5, and 7 includes the groove 40, as before, which however in this modification communicates by means of a radial opening 20 48, through part 126, with a depression or fuel cup 50 formed in a separate nozzle part 52 extending crosswise of the plunger in an under cut groove. Nozzle 52 has one or 25 more openings 54 which register with openings 24 when the plunger is at the end of its compression stroke.

In both forms, fuel such as distillate or kerosene is introduced in successive charges, by any suitable means (not shown) through a passage 56 at the top of the pump cylinder, while the pump plunger is on its down stroke. When the plunger reaches the lower end of its stroke (and when the fuel is to be vaporized in exhaust gases), the passage 24 is uncovered. Preferably this is just before the end of the power stroke of piston 10, so that exhaust gases from the engine cylinder 12, under very considerable pressure, rush through passage 24 and fill the pump cylinder 22.

On the compression stroke of the pump plunger, the fuel vaporizes in the hot exhaust gases, the vaporization being aided by the mixing of the gases as they are forced 45 through the tortuous path in the passage through the plunger. At the end of the compression stroke, and shortly before the end of the compression stroke of piston 10, the vaporized fuel mixture is injected 50 through passages 24 into the combustion chamber 16. The pump plunger, and operating plunger 36, are operated by a suitable engine-driven cam or the like, against the resistance of the usual return spring 58.

While two illustrative plungers have been described in detail, it is not my intention to limit the scope of the invention to those particular constructions, or otherwise than by the terms of the appended claims.

60 I claim:

1. Fuel-injecting means for the power cylinder of an engine comprising, in combination with said power cylinder, a pump cylinder, a pump plunger in the pump cylinder 65 divided in a plane parallel to its axis and

with the parts so formed urged yieldingly apart against the pump cylinder wall, and means operative at the end of the stroke of the pump plunger for placing the power cylinder of the engine in communication with the space between the parts of the divided pump plunger. 70

2. Fuel-injecting means for the power cylinder of an engine comprising, in combination with said power cylinder, a pump cylinder, a pump plunger in the pump cylinder divided in a plane parallel to its axis and with the parts so formed urged yieldingly apart against the pump cylinder wall, and openings in the power cylinder wall and in 80 the adjacent part of said plunger which are arranged to communicate at the end of the stroke of the pump plunger for placing the power cylinder of the engine in communication with the space between the parts of the divided pump plunger. 85

3. A pump comprising a divided plunger, and means urging the parts of the plunger yieldingly apart, one part of the plunger having a passage formed in an axial direction on its plane face and opening at one end at the end of the plunger, and one of said parts of the plunger having a generally radial passage from its outer face which 90 communicates with the other end of the axial passage. 95

4. A pump comprising a divided plunger, one part of the plunger having a passage formed in an axial direction on its plane face and opening at one end at the end of the plunger, and one of said parts of the plunger having a generally radial passage from its outer face which communicates with the other end of the axial passage. 100

5. A pump comprising a divided plunger, one part of the plunger having a passage formed in an axial direction on its plane face and opening at one end at the end of the plunger, the same part of the plunger having a generally radial passage from its outer face 110 which communicates with the other end of the axial passage. 110

6. A pump plunger divided axially in two parts, with the plane face of at least one part grooved to form an axial passage from the end of the plunger inwardly, and with one part having an opening therethrough communicating with the inner end of said passage. 115

7. A pump plunger divided axially in two parts, with the plane face of at least one part grooved to form an axial passage from the end of the plunger inwardly, and with one part having an opening therethrough communicating with the inner end of said passage, said plunger having a plurality of springs arranged on opposite sides of said opening and urging the parts of the plunger away from each other. 120

8. A pump plunger divided axially in two 130

- parts, with the plane face of at least one part grooved to form an axial passage from the end of the plunger inwardly, and with one part having an opening therethrough communicating with the inner end of said passage, said plunger having a pair of radially-extending coil springs confined between said parts, one above and one below said opening.
10. A pump plunger divided axially to form two parts yieldingly urged apart, together with an operating plunger alined with one end of said pump plunger, the operating plunger having a tongue-and-groove connection with the ends of the parts of the pump plunger.
10. A pump plunger divided axially to form two parts yieldingly urged apart, together with an operating plunger alined with one end of said pump plunger, the operating plunger having a tongue-and-groove connection with the ends of the parts of the pump plunger, the tongue-and-groove connection extending parallel to the plane between the parts of the pump plunger.
11. A pump plunger divided axially to form two parts yieldingly urged apart, an operating plunger alined therewith and formed with an undercut groove across its end, each part of the pump plunger having an undercut tongue to fit in one side of said groove.
12. A pump plunger divided axially to form two parts yieldingly urged apart, an operating plunger alined therewith and formed with an undercut groove across its end, each part of the pump plunger having an undercut tongue to fit in one side of the groove, together with a plurality of springs confined between said parts and urging them away from each other.
13. A pump plunger divided axially to form two parts yieldingly urged apart, an operating plunger alined therewith and formed with an undercut groove across its end, each part of the pump plunger having an undercut tongue to fit in one side of the groove, together with yielding means arranged between said parts and urging them away from each other.
14. A pump plunger divided axially to form separated parts, and having a passage extending axially down the plane face of one of said parts and then through one of said parts to the outside of the plunger.
15. A pump plunger divided axially to form separated parts, and having a passage extending axially down the plane face of one of said parts and then through one of said parts to the outside of the plunger, at least a portion of said passage being formed with a series of sharp bends serving as baffles to mix fluid passing through the passage.
16. A pump plunger divided axially in two parts, one of which is formed with a radial passage permitting communication of the space between said parts with the outside of the plunger, said part having a transverse undercut groove across the outer end of said passage, together with a separate part fitting in said groove and formed with openings and having a depression over the end of said passage and from which said openings lead.
17. A pump plunger divided axially in two parts, one of which is formed with a radial passage permitting communication of the space between said parts with the outside of the plunger, said part having a transverse undercut groove across the outer end of said passage, together with a separate part fitting in said groove and formed with openings communicating with said passage.

In testimony whereof, I have hereunto signed my name.

HOWARD M. LEONARD.
